HAIR CURLER AND WAVER

Mary I. Peddle, Pawtucket, R. I.

Application May 7, 1936, Serial No. 78,503

1 Claim. (Cl. 132—38)

This invention relates to certain new and useful improvements in hair curlers and wavers.

The primary object of the invention is to provide a hair curler and waver of a character that is concealed when in use by the hair curled therearound so that the curler and waver may remain in the hair without the objectionable feature of being exposed.

A further object of the invention is to provide 10 a hair curler and waver of the foregoing character that is constructed of two flexible members capable of ready separation after having performed the function of producing a curl or wave in a lock of hair without disturbing the curl or 15 wave.

A still further object of the invention is to provide 20 a hair curler or waver formed of two adjustably connected and separable elements so that the device may be adjusted to accommodate the curling or waving of different amounts of hair.

With the above and other objects in view that will become apparent as the nature of the invention is better understood, the same consists in 25 the novel form, combination and arrangement of parts hereinafter more fully described, shown in the accompanying drawing and claimed.

In the drawing:—

Figure 1 is an elevational view of a hair curler 30 and waver constructed in accordance with the present invention, showing the two separably connected slidable sections;

Figure 2 is an elevational view, similar to Figure 1, showing a relatively wide lock of hair having 35 the device associated therewith;

Figure 3 is an elevational view, similar to Figure 2, showing the waver and curler adjusted for use with a relatively narrow lock of hair;

Figure 4 shows a lock of hair rolled on the device with the ends of the device in position to be bent into retaining position therefor;

Figure 5 is a detail view, partly in section of one member of the two part device in which the flexible strand carries a metallic end loop;

Figure 6 is a fragmentary elevational view 45 of one end of one of the elements formed of a single flexible strand that is split at one end to form a loop;

Figure 7 is an elevational view of another modification of hair curler and waver wherein the sliding connection between the two sections comprises guide loops spaced from the ends of the sections; and

Figure 8 is a perspective view of another form 55 of curler and waver in which a flexible leather

strap or ribbon is slidably associated with a flexible wire.

The hair curler is formed of a pair of flexible elements such as cords or wires, each element preferably being in the form of a wire strand 5 covered by a laced fabric or the like similar to electrical conductor wires. As shown in Figure 1, the device is formed of two wire strands 10 and 11, each having a return bent portion at one end constituting a loop 12 that is retained in position as at 13 while each of the strands 10 and 11 has a normally straight end 14. The two sections 10 and 11 are adjustably and slidably connected together by inserting the free end 14 of one strand through the loop 12 of the other 10 strand as illustrated and the distance between 15 the two loops 12 for accommodating groups of hair of different widths is varied by slidably adjusting the two strand sections 10 and 11. As 20 shown in Figure 2, a relatively wide group of hair H is shown positioned between the strands 10 and 11 and the loops 12, while in Figure 3 the relatively narrower group of hair N is shown 25 positioned between the two strands 10 and 11 with the loops 12 moved into closer proximity to each other.

With a group of hair positioned as illustrated in Figures 2 and 3, the curler or waver is rotated or rolled to wind the group of hair thereon as shown in Figure 4 and when the desired size 30 of roll has been attained, the free extending ends 14 together with the loops 12 are bent to underlie the hair roll R to be rendered invisible when 35 in use so that the wearer may appear in public with the devices entirely hidden from view. The 40 curlers may be readily removed from a roll of hair without disturbing the roll by straightening the ends thereof and slidably separating the two strand sections 10 and 11.

In the form of invention illustrated in Figure 45 5, the flexible strand 15 of each of the elements is provided on one end with a tubular metallic cap loop 16 removably secured thereto and through which the free end of the cooperating flexible strand is projected.

In Figure 6, the flexible strand 17 is split at one end to provide a guide loop 18.

In Figure 7, each of the flexible strands 19 is provided with a slip knot 20 spaced from the 50 end of the strands and through which the free end of the cooperating strand slidably extends.

In Figure 8, the flexible strand 21 has a flexible ribbon or leather strap 22 slidably associated therewith, the strap 20 being provided with a 55

perforation 23 adjacent each end through which the strand 21 slidably extends.

In addition to the foregoing description I may add that in the forms of the device shown in the various drawings as soon as the lock of hair has been rolled, the ends of both members may be bent over upon themselves so as to retain the curl, or one member may be entirely removed and the ends of the remaining member may be bent 10 to retain the curl in position.

My device will work equally well if one of the members is composed of more rigid material, such as thin metal or celluloid.

Where I have not employed metallic tips for 15 the ends of my curler, it has been my custom to treat the ends of the separate members with water-proof glue in order to prevent threads from unravelling.

From the above detailed description of the invention, it is believed that the construction and use thereof will at once be apparent and while there are herein shown and described the preferred embodiments of the invention, it is nevertheless to be understood that minor changes 5 may be made therein without departing from the spirit and scope of the invention as claimed.

What is claimed is:—

In a hair curler and waver, a pair of flexible 10 elements, each element having a return bent portion at one end with the terminal end anchored to its element to form a closed loop, each end loop receiving and forming a retaining guide for the unlooped end of the other flexible element. 15

MARY I. PEDDLE.
